US00D930729S

(12) **United States Design Patent** (10) **Patent No.:** **US D930,729 S**
(45) **Date of Patent:** **** Sep. 14, 2021**

(54) **CAMERA**

(71) Applicant: **FLIR Systems AB**, Taby (SE)

(72) Inventors: **OJ Ou**, Taipei (TW); **Anton Hoffman**, Taby (SE); **Christian Hogstedt**, Taby (SE); **Victor Ku**, Yorktown Heights, NY (US); **Niklas Briheim**, Stockholm (SE); **Andreas Lundback**, Stockholm (SE); **Markus Stridsberg**, Stockholm (SE)

(73) Assignee: **FLIR SYSTEMS AB**, Taby (SE)

(**) Term: **15 Years**

(21) Appl. No.: **29/675,383**

(22) Filed: **Dec. 31, 2018**

(51) **LOC (13) Cl. 16-01**

(52) **U.S. Cl.**

USPC **D16/206**

(57) **CLAIM**

The ornamental design for a camera, as shown and described.

DESCRIPTION

FIG. 1 is a front, right, and bottom perspective view of a camera embodying the new design;

FIG. 2 is a rear, left, and top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are shown for the purpose of illustrating portions of the camera that form no part of the claimed design.

1 Claim, 8 Drawing Sheets
